MULTIPLEX TELECOMMUNICATION
SYSTEM

William G. H. Finch, New York, N. Y.

Original application February 26, 1936, Serial No. 65,869, now Patent No. 2,047,863, dated July 14, 1936. Divided and this application June 24, 1936, Serial No. 86,902.

4 Claims. (Cl. 179—2)

5 My invention relates to telecommunications systems and more particularly relates to novel apparatus for and methods of multiplex carrier transmission of picture and other signals to remote points over telephone lines, and is a division of my application, Serial No. 65,869, filed February 26, 1936, which matured into Patent No. 2,047,863 on July 14, 1936.

10 The widest use which telepicture systems to-day enjoy is in connection with newspaper service which pictures of important news events are transmitted from or near its source to newspaper offices for publication. For such use, it is highly desirable that the picture be transmitted as near 15 to the scene as practicable. Heretofore, it has been proposed to use telephone lines which are usually available at almost any place for the transmission of pictures. Inasmuch as the telephone company, however, does not permit any 20 interconnection by a subscriber to its lines, it has been necessary to find some other than physical connection means for transmitting picture signals over the telephone lines. It has been proposed that this might be accomplished by 25 acoustic coupling to the telephone line. Such a system comprised a loud speaker unit which transformed picture signals into corresponding sounds which in turn were impinged on the usual telephone microphone.

30 Although the acoustic method of inducing picture signals into the telephone line has still been proposed as recently as within the past few years, it has many inherent defects which render it impractical. The more serious of the many drawbacks of such an arrangement are the distorted frequency response characteristic of the usual 35 loud speaker, and the even more distorted frequency response characteristic of the carbon microphone ordinarily used in telephone systems.

40 Although for the transmission of speech, poor frequency characteristics are not material, as the ear tends to correct for audible distortions, they are serious in connection with telepicture systems where distortion would be visually evident on the 45 received picture.

I have discovered a novel electric coupling to the telephone lines which has a linear frequency characteristic with respect to the signals transmitted thereby. Specifically, my system contemplates a novel method of inductively inducing signals into the telephone line at the transmitter by a novel portable member which may be applied to any telephone subscriber station box.

50 The transmission of low frequencies, for example frequencies below 25 cycles, is greatly attenu-

ated in present telephone systems. Communication requiring signals below 25 cycles may accordingly not be directly transmitted thereby. By modulating an audio frequency carrier wave with such signals, they may then be readily transmitted over the telephone system. The original telecommunications signals are then obtained by demodulation at the receiver. The electrical inducing means of my present invention provides for the linear transmission and reception of such carrier signals. In telegraphy, printing telegraphy and picture transmission systems, such audio frequency carrier operation is preferable.

5 By establishing a linear wide frequency band transmission characteristic, for example, linear from 25 cycles to 5000 cycles over a telephone line, it is possible to transmit two independent telecommunications signals utilizing two independent audio frequency carrier waves. Simultaneous speech and telegraph or printing telegraph and telepicture transmission over a single telephone channel is accordingly practical without physical connection thereto, according to my present invention.

25 Among the advantages other than the well known economic advantages of utilizing a telephone system for telecommunications which my novel coupling means makes available, is the utilization of a portable transmitter. A newspaper reporter, for example, provided with my novel coupling arrangement, may be provided with a portable transmitter which he can employ at any office a picture which has immediate news value. 30 In doing so, he will in no way interfere with the normal operations of the telephone line other than to utilize it as any subscriber when he lifts the phone off the hook.

35 In a further modification of my invention, I contemplate transmitting the signals induced into the telephone line to the nearest of a number of strategically placed radio transmitting stations for the purpose of either simultaneous or subsequent transmission of the picture signals 45 from such station. This arrangement would not only reduce the telephone costs but would also provide quicker service for national coverage.

40 In accordance with my present invention, I contemplate utilizing the wide audio frequency channel for simultaneous transmission of several signals with corresponding independent carrier waves. For example, the telepicture transmission of the picture to the main office may be simultaneously accompanied by telegraphy or printing 55

telegraphy signals over the same lines but with an independent carrier frequency. Another modification resides in transmitting two independent pictures over the same channel, using separate independent carrier signals.

In accordance with still another modification of my present invention, I contemplate a high speed printing telegraph system employing a plurality of independent tones which are simultaneously transmitted and which correspond to, for example, a Baudot code combination for each character of the printing telegraph system. Corresponding filters at the receiving station are used to segregate the respective constant frequency tone impulses to actuate the printing telegraph receiver.

It is accordingly an object of my invention to provide novel methods of and means for electrically coupling to public telephone systems for the transmission and reception of signals between remote points.

Another object of my invention is to provide novel methods of a means for transmitting pictures over a telephone system.

A further object of my invention is to provide novel methods of and means for transmitting telecommunications signals across telephone lines, by modulating an audio frequency carrier wave and electrically inducing the resulting signals into a telephone system.

Still a further object of my invention is to provide novel methods of and means for transmitting pictures over a telephone line utilizing an audio frequency carrier wave which is electrically induced into the telephone system.

Another object of my present invention is to provide novel methods of and means for electrically coupling a telepicture receiver at a telephone receiving station for receiving signals without physical interconnection with the telephone system.

Another object of my invention is to linearly transmit two or more independent or interdependent telecommunications signals over a single telephone line without physical connection thereto.

A further object of my invention is to simultaneously transmit picture and printing telegraphy signals over a single telephone line without physical interconnection thereto.

Still a further object of my invention is to provide a high speed printing telegraph system employing a plurality of independent tone impulses which are combined to select the printing characters, over a telephone line without physical interconnection thereto.

These and other objects of my invention will become apparent in the following description taken in connection with the drawings, in which: Figure 1 is a schematic circuit diagram of a single channel telecommunication system corresponding to Figure 2 of the parent application, Serial No. 65,869, referred to above.

Figure 2 is an over-all transmission characteristic curve plotted with the ordinate as the voltage at the receiving station translator as received from a constant voltage signal transmitted over the frequency range, the transmission being uncompensated.

Figure 3 is a transmission characteristic of a compensation network necessary to compensate the characteristic of Figure 2 for linear transmission.

Figure 4 is an over-all transmission characteris-

tic between the transmitter and translator units of a compensated system.

Figure 5 is a schematic circuit diagram of a duplex intercommunication system employing two independent modulated carrier signals.

Figure 6 is a schematic illustration of a modified multiplex carrier wave communication system over a telephone line without physical connection thereto.

The audio frequency signals are inductively coupled into a public telephone system. The telephone system illustrated has a transmitter station 10, having a microphone transmitter 11 and ear-piece 12, connected by leads 13, 14 and 15 to the station phone box 16, operatively connected 15 to the receiver telephone station 17, having its carbon microphone 18 and ear-piece 19 which are connected by leads 20, 21 and 22 to the receiving station call-box 23, by the interstation leads 24 and 25.

I have here illustrated one of the several methods in which the induction coils 26 and 27 are generally connected in telephone systems. The particular connections of the induction coils in the system are not important, since in every case the effects described in conjunction with the illustrated connections will be effected. The dashed portion 24'-25' of the telephone line 24-25 represent all the auxiliary apparatus necessary to maintain the telephone stations 10 and 17 in operative relation. Included between the stations 10 and 17, as is well known, are repeating stations, batteries, ringers, etc.

At the transmitter station 10, the microphone 11 is connected to line 25 by lead 15. The microphone 11 circuit is completed by lead 14 to the line 24, with the primary 28 of induction coil 26 connected in series therewith. As is well known, the carbon microphone 10 requires a direct current energization which is supplied through the last mentioned series circuit arrangement. The telephone earpiece 12 is coupled as follows to the telephone lines to eliminate the passage of direct current therethrough: The earphone 12 is connected to the secondary 29 of the induction coil 26 by lead 13. The opposite side 40 of the secondary 29 is connected to line 25 in series with the condenser 30.

The primary 31 and secondary 32 of the receiver induction coil 27, together with condenser 33 are connected at the receiver microphone 18 and earpiece 19 in a manner similar to that at the transmitter 10 herein described.

The audio frequency signal generator 34 generates the signals to be transmitted over the telephone system 10-17. Generator 34 may, for example, produce picture signals to be transmitted, telegraphy signals or the like. An audio frequency oscillator 35 is operatively connected with the audio signal generator 34, producing at the output 36-37 of generator 34, a signal modulated carrier wave. The signal modulated carrier is amplified by audio frequency amplifier 38 and connected to the solenoid 40 by output leads 41-42. A compensation network 43 is shown connected between the solenoid 40 and the signal amplifier 38, the purpose of which will be described hereinafter.

The transmitter solenoid 40 is placed adjacent to the induction coil 26 to provide for optimum induction of the telecommunications signals therein. I have found that when the axis of solenoid 40 coincides with the axis of the induction coil 44, maximum signal energy transfer is had. The solenoid 40 is placed as close to as practicable 75

to one end of induction coil 26 to insure maximum signal induction. The phone box 16 is enclosed by a sheet metal cover 39 indicated in dotted lines. In a practical performance of the coupling arrangement according to my invention, therefore, one side of the solenoid 40 is juxtaposed with the metal cover 39 at a region so that its axis coincides with the induction coil 26 axis, or is as close thereto as physical conditions permit.

10 The region of optimum coupling is determined in the following manner. The audio frequency carrier or tone from generator 35 is induced to the line through amplifier 38, and impressed upon solenoid 40 as hereinabove described. This 15 operation is preliminary to the transmission of the telecommunication signals for optimum adjustments of the transmitting and receiving apparatus. Telephonic communications between stations 10 and 17 are established through automatic dialing or by telephone operators. The 20 solenoid 40 is placed close to one end of the induction coil 26. The tone or audio frequency carrier may be heard locally by the transmitter operator through earpiece 12. The position of 25 solenoid 40 is adjusted on box 16 with respect to induction coil 26, so that a tone of maximum intensity is heard by the operator in earpiece 12. A rapid and simple determination of the optimum coupling position is had in this manner.

30 The signals transmitted across the telephone lines 24-25 to the telephone receiving station 17 pass through the receiver induction coil 17 within the receiver call box 23. A corresponding electromagnetic field is set up about the induction coil 27 in correspondence with the transmitted signal variations. A receiver solenoid 45 is magnetically coupled with the induction coil 27 to pick-up the signals as transmitted from the transmitting station. The pick-up solenoid 45 is 35 connected to the input of an audio frequency amplifier 46 by input leads 47-48. The output of amplifier 46 is connected either directly to the translator 50 or in series with a detector station 51 where the higher frequency or tone is 40 to be removed or demodulated from the receiver signals. Where the detector 51 is employed, the signals at the input 52-53 to the translator will correspond exactly to the signals generated at the audio signal generator 34 of the transmitting station.

45 The solenoid 45 at the receiving station is positioned for a maximum signal transfer or pick-up with respect to receiver induction coil 27. This position is determined in a manner similar to that described at the transmitter, namely the axis of solenoid 45 preferably coincides with the axis of induction coil 27, and one end of solenoid 45 is juxtaposed on the metal casing 54 of the receiver phone box 23. The receiving 50 coil 45 is experimentally adjusted to this optimum position by listening to the tone in earpiece 61 and is rigidly clamped in place as described in application Serial No. 65,869 supra. Such adjustment is preferably made during the 55 transmission of a constant amplitude carrier from the transmitter. The optimum position may more accurately be indicated by an output meter (not shown) connected at the receiver audio amplifier 46 as will be evident to those skilled 60 in the art.

Figure 2 is a graphical representation of a typical overall transmission characteristic which I have obtained between a transmission and receiving station, corresponding to the ratio between the signals at the generator 34 and trans-

lator 50 of Figure 1. The curve 55 is plotted with frequency, in cycles per second, and with E, representing the received voltage at the translator 50. At the transmitting station, signals of constant amplitude were introduced to the audio amplifier 38 at frequencies extending from 25 cycles to 5000 cycles and beyond. Curve 55 demonstrates the substantial linearity of this method of transmission from 900 cycles to 5000 cycles as indicated by the corresponding horizontal portion of the curve 55. However, a peak 56 occurred in the region of 400 cycles; starting at 25 cycles rising to a maximum at about 400 cycles, and diminishing to the flat characteristic portion of curve 55 at about 800 or 900 cycles. With 10 the transmission characteristic illustrated in Figure 2, an audio frequency carrier of 3000 cycles may be used to transmit telecommunication signals with no frequency discrimination for the sidebands of the 3000 cycle carrier as will be understood by those skilled in the art.

If intermediate equipment between the telephone stations 10 and 17 introduce a cut-off frequency below 5000 cycles to the transmission characteristic, the audio frequency carrier may 25 accordingly be adjusted so that the sidebands may be uniformly transmitted. It is also practical to transmit a single sideband upon an audio frequency carrier, and utilize the linear transmission characteristic on single side band audio 30 frequency carrier transmission as is well known in the art.

Another important feature of my invention resides extending the linear characteristic transmission relation up from 25 cycles, by eliminating the effect of the peak 56 by inserting compensation network 43 between the transmitter solenoid 40 and the translator amplifier 38 output. The purpose of this network is to attenuate signals between 25 cycles and 900 cycles inversely 35 proportional to their peaked relation at 56 of Figure 2. In Figure 1, I illustrate a simple form of compensation network for this purpose. An inductance 51 and capacitance 58 are connected in series across solenoid 40 and connection leads 41-42. The inductance 51 and capacitance 58 are designed to be tuned to 400 cycles or the peak 50 56 frequency, in a manner well known in the art. The compensation network 43 will absorb signals to the greatest extent at the frequency it is tuned to, namely, 400 cycles, to correspond 55 to the peak of the induction coupling system herein described.

Figure 3 illustrates the transmission characteristic 60 of the compensation network 36. It will be seen that minimum 61 transmission occurs 55 at 400 cycles. The proportion of transmission decrease is made equal to the proportion of the peak 56 to the plateau 55 of Figure 2.

Figure 4 represents the overall transmission characteristic 62 corresponding to Figure 2 with the compensation network 43 connected as illustrated in Figure 1. The superposition of compensation network characteristic 60 of Figure 3, upon the transmission of characteristic 55-56 of Figure 2, produces the transmission characteristic 62 of Figure 4, which is substantially linear from 25 cycles to 5000 cycles and above.

It is accordingly evident that the electrical induction method for transmitting audio frequency signals according to my present invention, may be attained with substantially no amplitude discrimination with respect to the frequency. I have also found that the noise level of this transmission system is negligible as compared to the 75

telecommunications signal strength, resulting in an excellent signal to noise ratio.

The wide channel afforded by my present invention with no physical connection to the telephone lines may be utilized with more than one carrier wave transmission. Accordingly, in Figure 4 I have illustrated two audio frequency carriers, namely carrier No. 1 and carrier No. 2. Carrier No. 1 may, for example, be a tone of 1500 cycles, and carrier No. 2, a tone of 3500 cycles. The flat frequency characteristic 62 of the system permits the side-bands of the carriers Nos. 1 and 2, representing independent or interdependent telecommunications signals, to be transmitted without any signal discrimination or interference.

The utilization of two carriers as herein described may be for simultaneous telegraphy and printing telegraphy, or telegraphy and speech, or telepicture and speech, or the simultaneous transmission of two independent similar systems, for example, two facsimile pictures being simultaneously transmitted. Another modification for utilizing the wide audio frequency channel with two independent audio frequency carriers is to simultaneously transmit adjacent lines of a picture being scanned with two scanners oppositely disposed upon the picture drum, so as to cut in half the time for transmitting a single picture. Such a system requires each of the audio frequency carriers to be associated with one of the corresponding alternate scanning lines of the picture being transmitted, to actuate corresponding alternate telepicture translators for simultaneously reproducing the predetermined alternate picture lines at the receiver.

Figure 5 is a schematic circuit diagram of a modification of my invention wherein a plurality of independent signals are transmitted over respective independent carrier frequency. The transmitter telephone station 63 is placed in operative connection with the receiver telephone station 64 over telephone line 65. Transmitter No. 1 comprises an audio frequency signal generator which generates audio frequency signals to be transmitted, and an audio frequency amplifier for amplifying these signals to a proper voltage for actuating the corresponding transmitter solenoid 65. Carrier No. 1 is introduced to the transmitter No. 1 and may, for example, be an audio frequency corresponding to carrier No. 1 shown in Figure 4, namely 1500 cycles.

Transmitter No. 2 represents a second audio frequency signal transmitter which is coupled to the telephone system through solenoid 66. Carrier No. 2 is used in conjunction with transmitter No. 2 and corresponds to carrier No. 2 of Figure 4 of a value of 3500 cycles. The signals to be independently and simultaneously transmitted from transmitters Nos. 1 and 2 over telephone system 63-64 are respectively coupled to the phone box 67 of the transmitter station 63 through solenoids 65 and 66. Their respective carriers Nos. 1 and 2 are sufficiently separated so that the side bands of the corresponding modulated signals do not interfere. The solenoids 65 and 66 are mounted upon the phone box 67 in optimum coupling relation with the induction coil 68 contained therein. A common yoke 69 is indicated in dotted lines for properly supporting solenoids 65 and 66 upon phone box 67.

A compensation network is connected at the output of the transmitter which transmits frequencies falling within the region of the peak portion 56 of the transmission characteristic as indicated in Figure 2. In this illustration of Figure

5, the compensation network is connected in the circuit of transmitter No. 1 since it utilizes the lower carrier frequency. A filter circuit is connected between solenoids 65 and 66 and their respective transmitters in order to insure separation of the side bands between the two modulated carrier signals as will be evident to those skilled in the art.

At the phone box 70 of the receiving station 64, solenoids 71 and 72 are arranged on opposite sides of the induction coil 73. The received signals generate corresponding electromagnetic waves which are picked-up by the solenoids 71 and 72. Solenoid 71 is coupled to a corresponding translator No. 1; and solenoid 72, to translator No. 2. Filter No. 1' is inserted between solenoid 71 and the translator No. 1 and is designed to pass frequencies corresponding to those transmitted through filter No. 1 at the transmitter. In a similar manner, filter No. 2' is inserted between solenoid 72 and translator No. 2 to insure the reception at translator No. 2 of the frequency band transmitted across filter No. 2. A common supporter yoke 74 is preferably used for the solenoids 71 and 72 similar to the yoke 69 at the transmitting station.

The translators Nos. 1 and 2 correspond to independent receiver stations embodying audio frequency amplifier 46, detector 51 and translator 50, as illustrated in Figure 1. The duplex transmission system employing two independent carriers accordingly transmits audio frequency signals generated at transmitters Nos. 1 and 2.

The duplex transmission system employing two independent carriers, accordingly transmits over 35 the telephone system 63-64, audio frequency signals generate at transmitters Nos. 1 and 2 which modulate respective independent carrier frequencies, the corresponding translators Nos. 1 and 2 receiving their respective signals and independently translating them as will now be evident to those skilled in the art.

The telecommunication system illustrated in Figure 5 may be employed in several modifications. Transmitter No. 1 may, for example, be a printing telegraph system whilst transmitter No. 2 may be used to transmit picture simultaneously. Translator No. 1 accordingly would translate the messages of the printing telegraph, while translator No. 2 reproduces the transmitted pictures. A similar modification would result when the telepicture signals are transmitted over the higher carrier, 3500 or 4000 cycles corresponding to transmitter No. 2 of Figure 5, and voice communication is impressed across solenoid 65 through filter No. 1, filter No. 1 being designed to cut-off the frequency above 2000 cycles so that they may not interfere with the frequency band of transmitter No. 2. When speech is employed, it is not necessary to employ a carrier No. 1 frequency and the frequency range between 25 and 2000 cycles may be directly transmitted and correspondingly received through filter No. 1' at the translator No. 1. In this case, transmitter No. 1 utilizes a microphone while translator No. 1 employs an earpiece.

A single solenoid is employed for inductively coupling a plurality of independent units to the telephone system. Referring to Figure 6, operative connection is established between telephone stations 75 and 76 over the telephone line 77. The transmitter telephone station phone box 78 is coupled with the transmitting solenoid 79 in a manner similar to the hereinabove described modification.

Three independent transmitters, namely A, B and C, are shown coupled to the transformer 80 windings 81, 82 and 83 respectively. The secondary winding 84 of transformer 80 is connected 5 to the transmitter solenoid 79 which is placed in optimum coupling relationship with the induction coil 85 within phone box 78.

It is to be understood that the transmitters A, B and C comprise their respective audio frequency signal generator and audio frequency amplifier together with independent carrier frequencies. The carrier frequencies for transmitters A, B and C should be spaced along the audio frequency spectrum so that their respective side 10 bands due to the modulating signals do not interfere, as will be understood by those skilled in the art.

In order to provide a substantially linear transmission frequency characteristic for the system as 20 a whole, the transmitters A, B and C which generate signals lying within the band, which is normally non-linear, comprise proper compensating networks, for example, corresponding to network 43 of Figure 1, in order to effect linear 25 transmission of the respective transmitter signals.

The signals from primary windings 81, 82 and 30 83 of transformer 80 are accordingly spaced so as to be non-interfering, and their effect upon the secondary winding 84 is the super-position of the plurality of modulated carriers. The plurality of modulated carrier frequency waves are induced across the telephone system 75-76 through the solenoid 79 as will now be understood.

35 The signals induced across the telephone line 77 to the receiving station 76 pass through the induction coil 86 located within the receiver phone box 87 and produces electromagnetic waves corresponding to the transmitted signals. A receiver solenoid 88 placed in optimum coupled relationship with the induction coil 86 picks-up the signals and conducts them to the primary 89 of the receiver transformer 90. Transformer 90 contains three secondary windings 91, 92 and 93 40 which are respectively connected to translating units A, B and C through corresponding filter units A, B and C.

The voltage induced to the secondary windings of transformer 90 by primary winding 89 corresponds to voltage at the output winding 84 of transmitter transformer 80. This voltage is induced across all the secondary windings 91, 92 and 93. However, by providing suitable filters in the circuits between the secondary windings to the 50 translator units, suitable segregation of the combined signal voltages is had. For example, filter unit A, connected to the input of translator A, is designed having a transmission frequency characteristic encompassing the band of frequencies 55 at the output of transmitter A, and substantially cutting-off signals outside this band width. In a similar manner, filter B, connected to the input of translator B, is designed to transmit only the frequency band from transmitter B; and filter 60 C, connected to translator C, to transmit the band of transmitter C.

It will now be evident that a plurality of modulated carrier wave signal bands lying within the transmission frequency range over the telephone 70 system 75-76, may be transmitted without physical interconnection with the telephone system, but by electromagnetic induction at the transmitter and receiver. It is to be understood that a greater number of independent transmitter 75 units may be used over the frequency channel

which, for example, may extend from 25 cycles to 5000 or even 7000 cycles, by employing single side-band transmission of the signals. As is known to those skilled in the art, a modulated carrier wave normally comprises two sets of side-bands on either side of the carrier frequency. By suppressing one of the side-bands, practical transmission of the audio frequency signals may be accomplished with a single side-band. The respective filter units at the receiving station are designed 10 to pass a predetermined frequency band corresponding to the signals to be introduced to the respective translator unit.

The transmitter units schematically illustrated as A, B and C, may be any type of audio frequency 15 signal generator such as a telepicture set for transmitting pictures or written messages, a telegraph set, a printing telegraph unit, a speech or microphone unit, etc. Although I have illustrated three units, A, B and C, it will be obvious that 20 any number of such units may be used simultaneously in this modification as long as their frequency bands are properly chosen over the transmission characteristic so as to be non-interfering.

25 Although I have illustrated transmitter units A, B and C independently associated with the transformer 80 and have stated that these transmitter units comprise separate amplifiers, it is to be understood that a common amplifier unit 30 for the signals may be employed between the secondary 84 of the coupling transformer 80 and the induction solenoid 79. The primaries 81, 82 and 83 of the coupling transformer 80 in this modification, will be connected to the outputs 35 of signal generator units corresponding to units A, B and C, these signal generating units comprising the respective carrier frequency sources and the independent audio signals to be transmitted. A common amplifier unit is accordingly 40 more economical and compact for the plurality of signal bands. In a similar manner, the amplifier units associated with translator units A, B and C at the receiving station may be combined into a common amplifying unit inserted at the output 45 of receiving solenoid 88 connected between solenoid 88 and primary winding 89 of coupling transformer 90. The filter units A, B and C and the associated translator units A, B and C in this modification are respectively connected to the 50 secondary windings 91, 92 and 93 of coupling transformer 90.

Another modification following along the lines of the modification illustrated in Figure 6, resides in a novel high speed printing telegraph system 55 employing individual tones or frequencies. The five code combinations, for example, Baudot code combinations, of the characters to be transmitted may be associated with an individual frequency. The five frequencies are sufficiently spaced along 60 the frequency transmission channel to avoid interference and also permit suitable filtering action so that the receiving station may segregate the five frequencies to actuate corresponding selector units. In accordance with this printing telegraphy system, each character to be transmitted causes a particular code combination of the five frequencies or tones to be transmitted, the receiving station contains five selector units 65 individually tuned to the five tones, and the proper character at the transmitting station is selected to be impressed upon the message tape. A sixth tone may be used as the marking impulse, although the marking mechanism may be 70 75

under the control of the combined signal effect during each character transmission.

Although I have described preferred embodiments for carrying out my present invention, it will be evident to those skilled in the art that modifications falling within the spirit and scope of my invention are feasible and accordingly I do not intend to be limited except as set forth in the following claims.

10 1. I claim:

1. In a signalling system over a telephone line having a telephone station at each end and a phone box including an induction coil associated with each station: means for producing a first 15 audio frequency current band in the range of 1500 cycles per second; means for producing an independent second audio frequency current band in the range of 3500 cycles per second; and means at one telephone station for transmitting said first 20 and second independent audio frequency current bands across said telephone line comprising a first and second solenoid operatively connected respectively to said first and second audio frequency band currents, said solenoids being electromagnetically coupled with said induction coil associated with said first mentioned station; a common U-shaped yoke for supporting said solenoids on opposite sides of the associated phone box in optimum coupling relation with said induction coil 25 30 and compensation means connected in said first audio frequency current circuit designed to transform the lower frequencies to provide a substantially linear transmission frequency characteristic for said transmitted bands.

35 2. In a signalling system over a telephone line having a telephone station at each end and a phone box including an induction coil associated with each station: means for producing a first audio frequency current band in the range of 1500 40 cycles per second; means for producing an independent second audio frequency current band in the range of 3500 cycles per second; means at one telephone station for transmitting said first and second independent audio frequency current 45 bands across said telephone line, comprising a first and second solenoid operatively connected respectively to said first and second audio frequency band currents, said solenoid being electromagnetically coupled with said induction coil associated with said first mentioned station, a common U-shaped yoke for supporting said solenoids on opposite sides of the associated phone box in optimum coupling relation with said induction coil, and compensation means connected in said 50 55 audio frequency current circuits for providing a substantially linear transmission frequency characteristic for said transmitted bands; means at the second telephone station for receiving said transmitted frequency bands comprising a third and fourth solenoid electromagnetically coupled with the induction coil associated with said second station and a second U-shaped yoke for supporting said third and fourth solenoids on opposite sides of said second station phone box in optimum 60 65 coupling relation with the associated induction

coil; and means for translating said first and second frequency bands connected respectively to said third and fourth solenoids.

3. In a signalling system over a telephone line having a telephone station at each end and a phone box including an induction coil associated with each station: means for producing a first audio frequency current band to be transmitted comprising a first carrier frequency current source of the order of 1500 cycles per second, 10 means for modulating said first carrier current in accordance with first signals to be transmitted, and means for amplifying the first modulated carrier current; means for producing an independent second audio frequency current band to be transmitted comprising a second carrier frequency current source of the order of 3500 cycles per second, means for modulating said second carrier current in accordance with second signals to be transmitted, and means for amplifying the 20 second modulated carrier currents; and means at one telephone station for transmitting said first and second independent audio frequency current bands across said telephone line comprising a first and second solenoid operatively connected 25 respectively to said first and second audio frequency band currents, said solenoids being electromagnetically coupled with said induction coil associated with said first mentioned station, a common U-shaped yoke for supporting said solenoids on opposite sides of the associated phone box in optimum coupling relation with said induction coil, and compensation means connected in said first audio frequency current circuit for 30 35 providing a substantially linear transmission frequency characteristic for said transmitted bands.

4. In a signalling system over a telephone line having a telephone station at each end and a phone box including an induction coil associated with each station: a plurality of independent generators of signals to be transmitted; a carrier frequency current source associated with each of said signal generator, said carriers being spaced within the 5000 cycle band of the telephone system; means for modulating said carrier frequency currents by said corresponding signals to be transmitted for producing a plurality of independent modulated carrier frequency bands; means at one telephone station for transmitting said plurality of frequency bands across the telephone line comprising a solenoid electromagnetically coupled with the induction coil associated with said first mentioned station and a compensation network connected in the transmitting circuit for providing a substantially linear transmission frequency characteristic for the transmitted bands across the telephone circuit; and means at the second telephone station for receiving and translating said plurality of frequency bands comprising a solenoid electromagnetically coupled with the induction coil associated with said second station, and a plurality of translating units individual to each of said frequency bands.
